UNITED STATES PATENT OFFICE.

DAVID MOSMAN, OF WEST MERIDEN, CONNECTICUT.

DESIGN FOR A LAMP-STAND.

Specification forming part of Design No. 6,490, dated March 11, 1873.

To all whom it may concern:

Be it known that I, DAVID MOSMAN, of West Meriden, in the county of New Haven and State of Connecticut, have invented or produced a new and original Design for a Lamp-Stand, the nature of which will be understood from the accompanying photographic illustration and the following description.

The letter *a* indicates the foot or base, upon which is the figure of a double-faced human head, *b*, supporting the body of the lamp *c*.

The shape of the foot *a* and the body of the lamp *c* may be varied at discretion, as their

shapes are not essential features of the design. The essential feature is the double-faced human head; and

I claim as my invention or production—

The design for a lamp-stand, composed of a double-faced human head springing from a foot, *a*, and supporting the body of the lamp *c*, the whole having an appearance substantially as shown and described.

DAVID MOSMAN.
